SKATE WHEEL AND METHOD OF
PRODUCING SAME

Leland G. Knapp, Chicago, Ill., assignor to Montgomery Ward & Co., Incorporated, Chicago, Ill., a corporation of Illinois

Application April 21, 1933, Serial No. 667,189

2 Claims. (Cl. 208—181)

The primary object of the present invention is to improve the construction of wheels used with roller skates so as to render them more durable and lasting.

As now constructed, wheels employed for the purposes indicated wear out quickly. They are incapable of resisting the rough usage to which they are most commonly subjected, as when the user skates upon cement and concrete walks and other surfaces offering high abrasive action to the wheels. In the general form and construction of skate wheels employed in the present-day skate only a relatively small quantity of metal is present in their rims. This is due to the fact that the wheels are formed by stamping and bending, and the rims are constituted by overlapping layers which provide but little thickness. The outer layer, therefore, receives the direct wear and when this outer layer becomes worn the life of the wheel is gone. A new wheel must be substituted if use of the skate is to be continued. The present invention aims to provide a novel form of skate wheel by which the objections and disadvantages above pointed out are overcome. It contemplates a wheel wherein the rim is formed of a single thickness of massed metal to provide the necessary wear-resisting properties to meet the rough usage to which the wheel is subjected, thereby strengthening the wheel and imparting to the same greater durability and longevity.

A further object of the present invention is the provision of a wheel of the character referred to embodying in its construction such an arrangement and organization of parts as will permit the same to be manufactured at relatively low cost, and thus enable its use in the low priced skates now found generally in commerce.

A further object of the invention is the provision of novel methods of manufacture by which the costs of production are reduced to the minimum, thereby contributing to the availability of the wheel for the general use to which the same is adapted.

Other objects and advantages of the invention will appear as the nature of the improvements is better understood, the invention consisting substantially in the novel construction and combination of parts, together with the methods of manufacture, hereinafter fully described, illustrated in the accompanying drawing, and pointed out in the appended claims.

In the drawing,

Fig. 1 is a side elevation of a skate wheel con-

structed in accordance with the present invention;

Fig. 2 is a vertical transverse sectional view thereof, on an enlarged scale, as on the line 2—2 of Fig. 1;

Fig. 3 is also a transverse sectional view of the wheel, the viewpoint being at right angles to that of Fig. 2, as on the line 3—3 of Fig. 2;

Fig. 4 is a transverse sectional view of the rim of the wheel and the fixed disk thereof, indicative of the manner by which these elements are united; and

Fig. 5 is a vertical transverse sectional view of the detachable or clamping disk.

Referring in detail to the drawing, the numeral 10 designates an elongated sleeve, which constitutes the hub of the herein described wheel. At the center of the sleeve 10 is located a collar 11, which is of integral formation with the sleeve. The periphery of the collar 11 is formed with an inwardly-tapering groove 12, and this groove receives a plurality of balls 13 which are adapted to travel therein, and constitute the anti-friction bearings of the wheel. The sloping walls of the groove 12 desirably extend at an angle of approximately 45° to the axis of the wheel.

Arranged at one side of the collar 11 is a fixed disk 14, a detachable clamping disk 15 being located at the opposite side of the collar 11, and, in the main, these disks are complementary in form and construction. Each of the disks 14 and 15 has a central opening 16, which is of sufficient diameter to receive one end of the hub or sleeve 10 to permit the disks to freely rotate about said sleeve. Immediately adjacent to each of the openings 16 the body of each of the disks 14 and 15 is bent inwardly to provide an inclined contact area 17, the inner faces of the latter bearing upon the balls 13, and thereby sustaining proper traveling contact between the disks and the balls. The formation of the contact area 17 results in a dishing of the disks 14 and 15 immediately next to the openings 16. Preferably, the contact faces of the areas 17 lie at an angle of approximately 45° to the axis of the wheel, 45 thereby insuring a proper support by the balls of the disks. In contiguous relation to the contact areas 17 the bodies of the disks 14 and 15 extend outwardly in straight lines radially of the wheel to provide clamping areas 18. In the assembled relation of the disks 14 and 15 the clamping areas 18 are substantially parallel with each other.

The clamping area 18 of the disk 14 terminates in a horizontally-disposed annular supporting 55

flange 19 which lies at right angles to the disk 14, a similar supporting flange 20 being formed on the detachable clamping disk 15, the flange 20 being reversely arranged to the flange 19, said flanges extending circumferentially of the disks 14 and 15, and being seated against the inner surface of a rim 21 which surrounds said flanges. This rim is of any desired thickness for adapting the same to resist wear at its outer surface, and inasmuch as the thickness may be varied the material of which the rim is formed, being metal, may be massed in the rim so as to prolong the life thereof, and thus reduce wear on the wheel to a minimum.

By reason of the flanges 19 and 20 being reversely arranged they afford support for the rim 21 from its center to its edges. A greatly strengthened rim for the wheel thereby is afforded, and the edges of the rim are supported against bending strains.

The flange 20 has formed at its free outer edge a radially-directed annular flange 22, the adjacent edge of the rim 21 being rabbetted, as at 23, to receive said flange 22. This construction sustains the detachable clamping disk 15 in proper relation to the rim 21 and the fixed disk 14, and guides the disk 15 in relation to the rim when these parts are being assembled.

The disks 14 and 15 are provided with perforations adapted to register and receive a series of rivets 24, whereby the clamping disk 15 and the fixed disk 14 are held together. These rivets extend through the webs of the disks, and are upset in order to hold the disks in tight relation with respect to each other. It will be observed, however, that the inner faces of the disks 14 and 15, adjacent the perforations which receive the rivets 24, are pressed inwardly to provide lugs 25, the lugs of each disk contacting the lugs of the other disk in the assembled relation of the disks, and thus affording a space 26 between the disks. The purpose of this will presently appear.

As hereinbefore stated, one of the objects of the present invention is the provision of novel methods of manufacture by which the costs of production are reduced to the minimum, thereby contributing to the availability of the wheel for the general use to which the same is adapted. In furtherance of this object, the invention contemplates a novel method for securing the disk 14 to the rim 21, and thereby binding these two elements of the wheel into a substantially integral construction so as to impart a high degree of strength and rigidity to the wheel. To this end the rim 21 is given its annular form by any improved means or method. The disk 14 is stamped to its configuration, its external diameter being such that when introduced to the rim 21 the disk will frictionally engage the inner face of the rim. With the rim 21 and the disk 14 positioned in a horizontal plane, as illustrated in Fig. 4, a ring of solder is placed at the juncture of the disk 14 and the inner face of the rim 21, at the space formed at this point, a suitable flux having been applied, and with the two parts thus assembled heat is applied, preferably by placing the parts in a soldering furnace. After the solder has melted the same penetrates into the space between the flange 19 of the disk 14 and the inner face of the rim 21 and, upon cooling, the parts are firmly united in a substantially fixed or integral relation. This is the preferred method of assembling these parts. However, spot welding, and similar methods, may be resorted to to fix the disk 14 in relation to the rim

21, and thereby anchor the disk 14 within the rim. By thus uniting the disk 14 and the rim, the assembly and organization of the parts of the wheel may be expedited, it being merely necessary to introduce the hub 10 to the opening 16 of the disk, with the associated balls 13, and thereupon to position the clamping disk 15 upon the disk 14, the rivets 24 then being applied to tie the disks together, and effectually apply the rim 23 of the disk 15 to the rabbetted edge of the rim 21. In such application of the disk 15 to the disk 14, the lugs 25 of each disk bear against the lugs of the other disk, separating the webs thereof in the manner hereinbefore pointed out. Should it happen in assembling the disk 14 to the rim 21 that a surplus of solder remain at the joint between these parts, the spaced relation of the disks 14 and 15 will overcome the necessity of removal of such surplus, and the clamping disk 15 may be properly positioned on the rim without regard to the presence of such surplus of solder. In the ordinary application of the solder the quantity thereof may be properly gauged to preclude the presence of any surplus.

Like the disk 14, the disk 15 may be stamped to its required configuration.

From the foregoing description it is apparent that the rim 21 of the wheel is of a single thickness of massed metal, which thickness may be increased or diminished to the desired extent, but of such degree of thickness as to afford high resisting capacity to the rough surfaces over which the wheel usually travels in the ordinary usage to which roller skates are subjected. In the wear exerted on the rim 21 the entire mass of the metal therein responds thereto, and even though the entire thickness of the rim may be worn away, and thereby expose the flanges 19 and 20, these flanges still will serve as a rim for the wheel, and as a bearing surface with which to contact the roadway over which the wheel is traveling.

The present invention sharply distinguishes from the construction of skate wheel now commonly employed because of the single thickness of the rim 21, which, by such single thickness, masses the metal in the rim. The wear is received by this massed metal, and because of the thickness of the same it is obvious that there is greater durability and longevity to the wheel, with greater wear-resisting properties to meet the rough usage to which the wheel is subjected.

In producing the herein described wheel structure, the rim 21 is pack hardened or case hardened so as to further increase its wear-resisting properties without rendering the same of such brittleness as to break under the wear to which it is subjected. The disks 14 and 15 are also hardened to increase their strength.

When the wheel is assembled in the skate suitable closure caps may be used therewith in order to protect the openings 16 of the disks 14 and 15 against the ingress of sand, dirt, and other matter which may interfere with the free running of the balls 13 in relation to the hub 10 and the disks 14 and 15.

I claim:

1. In a wheel of the class described, the combination with a sleeve having a ball runway, and a series of balls arranged in said runway, of a rim surrounding said sleeve, and a plurality of disks arranged within the rim and disposed at opposite sides of said ball runway, each of said disks being provided with a peripheral flange extending at an angle to the disk and seated against the inner

face of the rim, said disks being provided with contact areas for engagement with said balls to establish an anti-friction bearing between the disks and said sleeve, one of said disks being fixedly related to said rim, the other disk being detachably related to the rim and to the fixed disk and serving to clamp the balls in said runway, the inner faces of said disks being provided with projections adapted to contact and space apart said disks in their assembled relation, and means for connecting said disks.

2. In a wheel of the class described, the combination with a sleeve having a ball runway, and a series of balls arranged in said runway, of a rim surrounding said sleeve, and a plurality of disks arranged within the rim and disposed on opposite sides of said ball runway, each of said disks being provided with a peripheral flange extending at

right angles thereto and seated against the inner face of the rim, said disks being offset adjacent to said balls to provide contact areas for engagement with said balls to establish an anti-friction bearing between the disks and said sleeve, one of said disks being fixedly related to said rim, the other disk being detachably related to the rim and to the fixed disk and serving to clamp the balls in said runway, the clamping disk having a radially-directed annular flange at its free outer edge, the adjacent edge of the rim being rabbed to receive said radially-directed flange, whereby the detachably clamping disk is sustained in proper relation to said rim and the fixed disk, and is guided in relation to the rim when the parts are being assembled, and means for connecting said disks.

LELAND G. KNAPP.
